ELECTRIC RELAY

Harold W. Williams, Jersey City, and Donald H. Baum, Ridgewood, N. J., assignors to Westinghouse Electric Elevator Company, Jersey City, N. J., a corporation of Illinois

Application January 12, 1939, Serial No. 250,560

5 Claims. (Cl. 175—336)

Our invention relates to electric relays and contactors, and more particularly to the operation of the armatures of such relays and contactors.

5 In the operation of electrical devices such as relays, contactors and switches as heretofore constructed considerable difficulty has been encountered because of the noise caused by the blows struck by the armatures against the cores to 10 which they are attracted, and also by reason of the tendency of the armatures to bounce when they reach their full open or full closed positions. When the impact of the armature against the core of a relay causes a bounce, it often causes 15 excessive arcing and wear on the contact members of the switches operated by the armature.

The noise and bounce are particularly objectionable where the devices are mounted upon heavy slate panels or other rigid structures. In 20 many instances the heavy blow struck by the armature is transmitted to the whole panel and the supporting structure like the blow of a hammer on the panel. In some cases it has been found that the armatures strike the cores so 25 hard that vibration may be felt in the angle iron frame supports for the panels.

Therefore, it is an object of our invention to provide a relay or contactor in which the noise and bounce resulting from the operation of the 30 armature shall be eliminated as nearly as possible.

Another object is to provide a relay or contactor in which the contact members operated thereby shall be free from excessive arcing and wear.

35 For a better understanding of our invention, reference may be had to the accompanying drawing, in which:

Figure 1 is a top plan view of a relay or contactor constructed in accordance with our invention,

40 Fig. 2 is a view in side elevation of the relay or contactor illustrated in Fig. 1,

Fig. 3 is an enlarged detail view in side elevation of the friction device on the upper end of the stop rod in the relay illustrated in Figs. 1 and 45 2, and

Fig. 4 is a view in end elevation of the friction device shown in Fig. 3.

Referring more particularly to the drawing, we 50 have illustrated a relay or contactor 10 as comprising a core 11, a coil 12 for energizing the core and an armature 13 for operation by the core. The core 11 is seated in an armature base 15 and both parts are retained in correct position on a 55 panel 14 by a cap screw 16 which passes upwardly

through the panel, the armature base and into the lower end of the core. The coil 12 is disposed around the core 11 and is retained in position thereon by a suitable nut 17.

The armature base has a pair of side wings or 5 arms 18 and 19 that extend upwardly along the sides of the core 12 to provide a pivotal mounting for the armature 13. The armature is provided with a pair of downwardly extending side arms or wings 21 and 22 that embrace the upwardly extending arms 18 and 19 on the armature base and are pivotally mounted thereon by a pivot pin 23 disposed in transverse holes through the arms of the armature and the armature base. The pivot pin is located near the rear end of the armature so that the front end 15 of the armature may move into and out of engagement with the core when the core is energized and deenergized.

The rear portion 24 of the armature is bent 20 downward slightly and is provided with a hole in which the upper end of a tension spring 25 is hooked. The lower end of the spring is hooked through the upper end of an eye-bolt 26, the lower end of which passes through the panel 14 25 and is secured therein by a pair of nuts 27. The spring 25 biases the armature 13 away from the core 11 and is so selected as to strength that, when the core 11 is energized, its magnetic pull will overcome the tension of the spring and cause 30 the armature to close quickly against the core.

A main finger board 30 and an auxiliary finger board 31, both of insulating material, are mounted upon and secured to the upper surface of the armature by a plurality of rivets 32 for use in supporting and operating contact finger arms when the armature is attracted by or released by the core.

45 A main contact finger 33 is mounted upon the main finger board 30 by a tubular rivet 34 and a pivot pin 35. The tubular rivet 34 is rigidly mounted in the finger board and the right-hand end of the main finger is loosely disposed thereon so that the left-hand end of the finger may move a short distance with reference to the finger board while the right-hand end pivots on the rivet. The pivot pin 35 is disposed upwardly 45 through the left-hand end of the finger board and through a hole in the main finger. A nut 37 50 and washer 38 are disposed on the free end of the pivot pin to maintain a spring 39 in compression between the washer and the upper face of the main finger. Inasmuch as the head of the pin 55 is disposed on the underside of the finger board,

the compression spring biases the finger against the board.

A contact member 40 of extruded copper is fixed on the left-hand end of the contact finger by a machine screw 41 in position to engage a cooperating main contact member 42 when the armature is released by the core and is biased away therefrom by the tension spring 25. The contact member 42 is supported in a U-shaped base 10 of strap copper or other conducting material by means of a screw bolt 44. The lower end of the U base rests on the slate panel 14 and is secured in position thereon by means of a bolt 45 and a placement clip 46.

15 By means of this construction it will be seen that when the armature is released by the core, the tension of the spring 25 will cause it to move to its open position, thereby moving the finger arm 33 to slap the contact member 40 down on the contact member 42, thus closing the main contact members. The compression spring 39 on the pivot pin 35 will permit the rear end of the armature to move past the point where the contact members engage, thereby maintaining a force against the closed contact members to keep them in good contact while the armature is open. The main contact member 42 may be constructed of any suitable material such as a compound of copper and carbon, or carbon and graphite.

20 30 If the main contact members are provided for carrying a heavy load they may be provided with an arc suppressing horn 47 and a blowout coil 48, the blowout coil being wound around one arm of the U strap 43 and having its one end connected to the horn and its other end connected to a suitable lead-in connector 49. A pair of blowout shields 51 and 52 are provided for shielding the arcing to the arc suppressing horn. The shields are mounted on the sides of the main contact member 42 between the upper ends of the U strap, and are retained in position by the screw bolt 44 and a lower screw bolt 53. The line 54 in the upper left-hand corner of Fig. 2 represents the point where the shield 52 is broken away to permit a view of the main contact members. A conducting cable 55 is provided for electrically connecting the main finger 33 with the circuit it is to control. The left-hand end of the cable is connected to the finger by a screw 56 and its right-hand end is connected to a lead-in connector 57 disposed in the panel 14.

25 35 The main board 30 and the auxiliary board 31 may be provided with as many additional contact fingers for operating additional pairs of contact members as may be desired, but only one auxiliary finger 60 is illustrated as secured to the board 31 by a pivot pin 61 and maintained in position by a compression spring 62. A flexible conductor 63 is connected to the auxiliary finger and has its lower end attached to a lead-in pin 63a, thus providing an electrical connection for the auxiliary finger. A contact member 64 is disposed on the free end of the contact finger in position to engage a cooperating contact member 65 mounted 40 on a supporting stud 66, the lower end of which is imbedded in the panel 14 and held there by means of a lead-in pin 67. A nut 68 on the stud 66 permits the contact member 65 to be easily adjusted to any desired height for engagement by the contact member 64.

45 50 In the operation of relays and contactors of the kind illustrated in the drawing, the armature strikes a heavy blow against its core when the core is energized to attract it thereto. The heavy blow creates unnecessary noise and in many instances even transmits vibrations to the panel on which the contactor is mounted. In order to reduce the noise resulting from the operation of the armature, we have provided a floating pole face 70 disposed to be loosely mounted in the core engaging face of the armature. The floating pole face or plug 70 is constructed of magnetizable material with a neck 71 and an enlarged cylindrical head or flange 72 somewhat like the shape of a flat button. The pole piece is movably disposed in a cylindrical chamber 73 in the armature with its neck 71 extending outwardly through a restricting flange 74 on the front end of the chamber 73. As illustrated in the drawing, the chamber or counterbored hole 73 is deeper than the thickness of the pole piece head 72 so as to permit the pole piece to move forward and backward in the chamber. The pole piece may be inserted in the chamber 73 before the auxiliary finger board 71 is mounted thereon. When the finger board is riveted to the armature, it closes the rear end of the chamber 73 and acts as a limiting and retaining rear wall for the floating pole piece.

55 60 Inasmuch as the floating pole face is constructed of magnetic material, it strikes the core in advance of the armature when the core is energized and reduces the noise of operation. We are not entirely clear as to the theory of what takes place during the operation, but we know that the construction described will reduce the noise of operation.

65 70 It may be that, when the coil 12 is energized to cause the core to attract the armature, the floating pole face being lighter than the armature and not biased away from the core, moves forward ahead of the armature toward the core under the magnetic attraction of the core until its movement relative to the armature is stopped by the flange 74. Next the armature and the floating pole piece move toward the core as one body. Then as the armature approaches close to the energized core, the pole piece hits the core first and is stopped from further movement but the armature continues its forward movement to the core, thus pushing the cylinder forward on the floating pole piece and separating the flange 74 on the armature from the flange 72 on the pole piece. The relative movement of the armature and the pole piece is not visible to the eye but is estimated to be about $\frac{3}{2}$ ".

75 80 Apparently, approximately the total flux set up by the coil on the core passes through the flanges on the armature and the pole face as they separate, thereby exerting a strong magnetic pull which tends to absorb the inertia of the armature and prevent it from over-traveling to any appreciable extent, and thus providing a magnetically elastic member at this point resulting in the very quiet operation of the armature. We have found in actual practice that the only noise present when the armature with its floating pole is attracted to the core is a slight tap as the pole face hits the core. Regardless of whether or not this theory of operation is correct, if the construction illustrated and described is used, it will result in almost noiseless armature operation.

85 90 In many relays and contactors of the character illustrated, it has been found that the operation of the armature is liable to result in a certain amount of bounce when the armature strikes the core, with the result that the contact members controlled by the closing movement of the armature will bounce or vibrate and thus cause arcing and wear. This arcing and wear may also occur

when the armature moves to its full open position with snap enough to cause some degree of bounce.

Even though the movable pole face construction provided has eliminated the heavy blows struck by the armature, some bounce may remain in the opening and closing operation of the armature. Therefore, we have provided means for further reducing the amount of bounce as the armature strikes the core and also when the armature moves to its full open position. This construction comprises a stop rod 80 mounted on the panel 14 and a friction device 81 for connecting the free end of the armature and the stop rod.

The lower end of the stop rod is movably mounted in the panel 14 and extends therethrough. A lower washer 82 and an upper washer 83 are fastened on the stop rod to limit its longitudinal movement in the panel. A sleeve 84 is disposed on the stop rod between the washers 82 and 83 to space them apart the predetermined distance it is desired to have the rod operate with lost motion connection in the panel. A pair of nuts 85 and 86 are disposed on the rod to hold the washers and spacing sleeve in the desired position on the rod. With this construction it is seen that the rod has a lost motion connection with the panel and is permitted to move up and down in the panel in the space defined by the washers 82 and 83. The face of each of the washers 82 and 83 may be provided with a sound-proofing material 87 to prevent any noise when the rod is stopped by the panel.

The free end of the armature is provided with an extended portion 89 that is bent downwardly in position to be connected to the stop rod 80 by the friction device 81. The friction device 81 (Figs. 3 and 4) comprises a U-shaped strap member 90, a friction block 91, a resilient member such as a compression spring 92, a pair of friction washers 93 and 94 and a compression bolt 95.

The U member 90 is seated on the extended free end of the armature and is firmly secured thereto as by welding at 91 so that it becomes practically a part of the end of the armature. The upper end of the stop rod extends upwardly through a hole 98 that passes through the armature end and the bottom of the U-shaped member 90. The friction block 91 is seated inside the U-shaped member 90 and its lower end is firmly screwed on the upper end of the stop rod extending through the hole 98.

In order to supply a predetermined amount of friction between the U-shaped member 90 and the stop rod, the block 91 is provided with a centrally-disposed transverse slot 100 which permits it to straddle the bolt 95 transversely mounted in the outer ends of the U-shaped member 90. The friction washers 93 and 94 may be constructed of suitable plastic material such as is sold under the trade-mark Micarta and are mounted on the bolt 95, one on each side of the block 91. A spacing sleeve 101 is disposed between the head of the bolt 95 and the washer 93. A similar spacing sleeve 103 is mounted between the washer 94 and a spring end member 104 on the bolt. The spring 92 is disposed on the bolt and is held between the spring-end member 104 and a spring-end 105 mounted on the outer end of the bolt by means of an adjustable nut 106. The sleeves 101 and 103 are slidably disposed in the upper end of the U-shaped member 90, hence it will be apparent that the nut 106 may be rotated to cause the

compression spring 92 to apply sufficient pressure to the friction washers 93 and 94 disposed against the sides of the block as to give the desired amount of friction between the free end of the armature and the stop rod. If it is desired to decrease the amount of friction, the nut 106 may be loosened, and, on the other hand, if it is desired to increase the amount of friction, the nut 106 may be tightened to effect the increase.

When the armature is attracted to the core by 10 energization of the coil 12, it will be apparent that the friction of the friction washers against the friction block will cause the stop rod 80 to move downwardly in the panel 14 until the stop washer 83 comes into contact with the panel. When 15 this point is reached, further downward movement of the rod is prevented, and this causes the friction device to come into play. As the armature continues its movement toward the core the friction washers slide along the friction block 20 91 with the amount of friction governed by the setting of the compression spring 92. Inasmuch as the washers are connected to the armature through the bolt 95 and the U-shaped member 90, the friction set up in the friction device brakes 25 or slows down the movement of the armature after the stop rod comes to rest. The stop washer 83 should be so disposed on the stop rod that the friction device becomes effective just as the armature engages the face of the core 11 and at 30 just that time which will prevent any bounce on the armature.

The limiting washer 82 on the lower end of the stop rod should be so located thereon as to move into engagement with the lower face of the 35 panel 14 as the armature nears its fully open position, so that further movement of the armature towards its open position will cause the friction washers to slide along the friction block and return to their starting point. This operation will also apply a braking effect to the armature as it reaches its fully open position, and, at the same time, will reset the stop rod and friction device 40 for again applying a braking effect to the armature when it moves to its closed position under 45 the energization of the coil 12. It will be evident that the stop rod may be connected to the panel 14 by any other lost-motion connecting means which will permit it to move freely a predetermined distance before causing the friction device 50 to become effective.

By reason of the apparatus described it can be seen that we have provided a relay or contactor in which the noise and bounce are practically eliminated, with the result there will be little 55 arcing and wear of the contact members operated by the armature. It will also be apparent that the construction of the floating pole face and the friction device are simple and inexpensive to manufacture, assemble and maintain in opera- 60 tion.

Although we have illustrated and described only one specific embodiment of our invention, it is to be understood that many changes therein and modifications thereof may be made without departing from the spirit and scope of our invention.

We claim as our invention:

1. In a contactor or relay, a base, a core 70 mounted on the base, means for energizing the core, an armature pivotally supported on the base with one end in position to be attracted to the armature when it is energized, an auxiliary pole piece movably mounted in the core engaging face of the armature to strike the core ahead of the 75

armature when it is attracted to the core, to lessen the striking blow of the armature, and a friction device connected between the core-engaging end of the armature and the base to prevent bouncing of the armature when it strikes the core.

2. In a contactor or relay, a base, a core mounted on the base, means for energizing the core, an armature pivotally supported on the base with one end in position to be attracted to the armature when it is energized, an auxiliary pole piece movably mounted in the core engaging face of the armature to strike the core ahead of the armature when it is attracted to the core, to lessen the striking blow of the armature, a friction rod connected to the base by a lost-motion connection, and a friction device mounted on the free end of the armature in position to engage the free end of the rod to retard the final closing and the final opening movements of the armature when operated by the core.

3. In an electrical device, a base, a magnetizable core mounted on the base, an armature, means for pivotally supporting the armature on the base in position for its free end to be attracted to the core, means for biasing the armature away from the core, means for energizing the core to attract the armature thereto, a friction device connected to the free end of the armature, and a lost-motion connector for connecting the friction device to the base to brake the final closing movement of the armature just before it engages the core when it is attracted by the energization of the core and for braking the final opening movement of the armature when it is released by deenergization of the core.

4. In an electrical device, a base, a magnetizable core mounted on the base, an armature, means for pivotally supporting the armature on the base in position for its free end to be at-

tracted to the core, means for biasing the armature away from the core, means for energizing the core to attract the armature thereto, a friction rod, a friction device connected to the free end of the armature for frictionally engaging one end of the friction rod, and a lost-motion connector for connecting the other end of the friction rod to the base to limit the movement of the friction rod to a predetermined distance, whereby the rod will move with the armature in its intermediate travel but will stop its movement as the armature approaches the end of its travel in either opening or closing to cause the friction device to retard the final movement of the armature and prevent bounce.

5. In an electrical device, a base, a magnetizable core mounted on the base, an armature, means for pivotally supporting the armature on the base in position for its free end to be attracted to the core, means for biasing the armature away from the core, means for energizing the core to attract the free end of the armature thereto, a friction rod having its one end movably disposed in the base and its other extending toward the free end of the armature, a pair of friction washers, means for supporting the friction washers on the free end of the armature in position to embrace the friction rod, resilient means for biasing the washers into frictional engagement with the rod, and a lost motion connector disposed on the base end of the rod for limiting the movement of the rod with reference to the base to a predetermined distance to cause the washers to frictionally slide on the rod for braking the movement of the armature and thereby keep it from bouncing as it reaches its full closed or open position.

HAROLD W. WILLIAMS.

DONALD H. BAUM.
